Specification for Design.

Patented Feb. 13, 1912.

Application filed June 19, 1911. Serial No. 634,193. Term of patent 7 years.

To all whom it may concern:

Be it known that I, HAROLD H. KENNEDY, a citizen of the United States, residing at Indianapolis, in the county of Marion and State of Indiana, have invented a new, original, and ornamental Design for a Vehicle-Body, of which the following is a specification.

In the accompanying drawing which forms a part hereof, Figure 1 is a side elevation of a vehicle body, showing my new design and Fig. 2 is an under side plan view of same.

I claim:

The ornamental design for a vehicle body, as shown.

In witness whereof, I have hereunto set my hand and seal at Indianapolis, Indiana, this 7th day of June, A. D. one thousand nine hundred and eleven.

HAROLD H. KENNEDY. [L. S.]
